DESIGN FOR A MANTELPIECE-ORNAMENT OR SIMILAR ARTICLE

Irving Defren, Brooklyn, N. Y.

Application May 3, 1939, Serial No. 84,750

Term of patent 3½ years

To all whom it may concern:

Be it known that I, Irving Defren, a citizen of the United States, residing in New York city, in the county of Kings and State of New York, have invented a new, original, and ornamental Design for a Mantelpiece-Ornament or Similar Article, of which the following is a specification, reference being had to the accompanying drawing, forming part thereof.

Fig. 1 is a perspective side view of the mantelpiece-ornament;

Fig. 2 is a front view of Fig. 1;

Fig. 3 is a rear view of Fig. 1, and

Fig. 4 is a top plan view thereof.

I claim:

The ornamental design for a mantelpiece-ornament or similar article, substantially as shown.

IRVING DEFREN,
